UNITED STATES PATENT OFFICE.

MONTRAVILLE M. WOOD, OF SCHENECTADY, NEW YORK, ASSIGNOR TO
GENERAL ELECTRIC COMPANY, A CORPORATION OF NEW YORK.

TROLLEY-HANGER.

SPECIFICATION forming part of Letters Patent No. 752,501, dated February 16, 1904.

Application filed August 8, 1903. Serial No. 168,738. (No model.)

To all whom it may concern:

Be it known that I, MONTRAVILLE M. WOOD, a citizen of the United States, residing at Schenectady, county of Schenectady, State of New York, have invented certain new and useful Improvements in Trolley - Hangers, of which the following is a specification.

The present invention relates to means for suspending and insulating electric conductors, and more particularly to hangers for trolley-wires.

The object of my invention is to provide a highly-efficient device of this character consisting of few parts, which may be readily taken apart by hand to permit a broken insulator to be replaced or for any other reason, reconnected, and securely locked against any tendency to work loose under the incessant shocks and vibrations to which devices of this class are subjected.

A further object of my invention is to provide an arrangement of the parts of a hanger so that the joints between them will be efficiently housed, to thereby prevent their becoming frozen or rusted together.

The invention comprises a suspender provided with an inverted-cup-shaped recess adapted to receive the head of an ordinary insulated stud, a nut or screw-threaded ring surrounding the insulated stud and having a drip-flange at its lower end and a threaded upper end provided with a shoulder adapted to be screwed into the cup-shaped recess against the shoulder on the lower surface of

the head of the stud and a locking-bolt longitudinally movable in an upwardly-extending recess in the suspender and adapted to engage at its outer end with notches formed in the periphery of the drip-flange and prevent the nut or screw-threaded ring from turning.

The invention will be readily understood by reference to the following description and the accompanying drawings, forming a part of this specification, in which—

Figure 1 is a part side elevation and part section of trolley-hanger embodying one form of my invention and to which is connected a

standard ear by means of an ordinary insulated stud, and Fig. 2 is a right-hand elevation of the same.

The suspender A shown in the drawings consists of a cylindrical body part 1 and a single downwardly-curved arm 2, in the end of which is an eye 3, through which the guy-wire may be attached in the usual manner. The body part 1 has formed in its lower surface an inverted-cup-shaped recess 4 of a size to readily receive the flat cylindrical head of an insulated stud B and having a plane end protected by a disk 5, of elastic material, against which the head of the stud normally presses, and a cylindrical side wall provided near its lower end with a screw-thread by which the nut or screw-threaded ring 6 is held in position. The nut or screw-threaded ring 6 has a shoulder 7 formed at its upper end to engage the lower surface of the head of the insulated stud B and a central aperture 8 of a slightly-greater diameter than the shank of the stud, so that the latter may pass readily therethrough. A downwardly - projecting flange or petticoat 9 is formed upon the lower end of the nut or ring 6 and strengthened by radial webs 10, and in the outer edge of the flange or petticoat 9 are cut a series of vertical slots 11, which coöperate with a locking-bolt 12 to hold the nut or threaded ring from turning and also serve to roughen the edge thereof, so that the hand may obtain a firm hold when disconnecting or assembling the parts.

The locking-bolt 12 is carried in an upwardly-extending recess 13, formed in the arm of the suspender, and a lug 14, projecting from the lower edge thereof into proximity to the petticoat or flange 9, and consists of a short metal bar provided with a tapered outer end 15 and a shoulder 16 at its lower edge adapted to engage a corresponding shoulder 17 formed in the recess 13 when raised out of engagement with the slots 11.

When it is desired to remove the insulated stud B for any cause, the nut or threaded ring 6 is first unlocked by raising the bolt 12

into inoperative position, either by the fingers or by passing a small tool, such as a screw-driver, between its beveled outer end and the flange or petticoat 9. The latter is then seized 5 by the hand and unscrewed from the suspender A. The stud B may now be unscrewed from the ear C by a wrench in the usual manner and withdrawn from the nut or threaded ring 6. In replacing the stud B these operations are reversed and the threaded ring or 10 nut screwed upon the head of the stud with as great force as desired and locked by slightly raising the outer end of the bolt 12 and permitting it to descend into one of the slots 11 15 in the edge of the flange or petticoat.

It is to be noted that according to my construction there are no crevices or joints in which water may lodge to freeze or rust or otherwise interfere with the free operation of 20 the parts and that the parts are so arranged and constructed that they cannot become injured or displaced by impact with the trolley head or pole.

I do not desire to restrict myself to the particular construction or form of parts shown 25 and described herein, for it is apparent that they may be changed and modified without departing from my invention.

What I claim as new, and desire to secure 30 by Letters Patent of the United States, is—

1. A hanger for electric conductors comprising a suspender provided with an inverted-cup-shaped recess adapted to receive the head of an insulated stud, a nut or threaded ring adapted to be screwed into the lower end of said recess, and means for locking said nut or ring in position.

2. A hanger for electric conductors comprising a suspender provided with an inverted-cup-shaped recess adapted to receive the head of an insulated stud, a nut or threaded ring adapted to be screwed into the lower end of said recess and provided with a drip-flange or pet-

ticoat, and means adapted to engage said flange or petticoat and lock said nut in position. 45

3. A hanger for electric conductors comprising a suspender provided with a recess adapted to receive the head of an insulated stud, a nut or threaded ring through which the said stud may pass and adapted to be screwed into said recess, and a longitudinally-movable bolt carried by said suspender and adapted to engage said nut or threaded ring to lock it in position.

4. A hanger for electric conductors comprising a suspender provided with a recess adapted to receive the head of an insulated stud and a bolt-recess, a nut or threaded ring adapted to be screwed into the first-mentioned recess, and a bolt located in the second recess and 60 adapted to engage and lock said nut or ring in position.

5. A hanger for electric conductors comprising a suspender provided with an inverted-cup-shaped recess and an inwardly-projecting recessed lug, a nut or threaded ring adapted to be screwed into said cup-shaped recess, and a bolt located in said recessed lug and adapted to engage and lock said nut or threaded ring in position. 65

6. A hanger for electric conductors comprising a suspender provided with an inverted-cup-shaped recess and an inwardly-projecting recessed lug, a nut or threaded ring adapted to be screwed into the cup-shaped recess to sustain an insulated stud therein and provided with a drip-flange having a series of slots in its outer edge, and a bolt located in said recessed lug and adapted to engage the slots in said drip-flange. 75

In witness whereof I have hereunto set my hand this 6th day of August, 1903.

MONTRAVILLE M. WOOD.
